SWIVEL TYPE FURNITURE-SUPPORTING GLIDE
George L. Congdon, Fort Atkinson, Wis., assignor to
Plastoco Corp., Oconomowoc, Wis., a corporation of
Wisconsin

Filed Sept. 12, 1963, Ser. No. 308,430
11 Claims. (Cl. 16—42)

This invention relates to a swivel type furniture-supporting glide.

In preferred embodiments of the invention, the glide includes a foot having an annular concave bearing surface of large radius with which a complementary convex annular bearing surface at the end of a leg-connected sleeve is in swiveled engagement. The sleeve has an internal shoulder formed to provide a seat for a knob or head which is carried by a stem connected with the glide foot and extending through the annular bearing, the shouldered portions of the sleeve being confined between the knob and the bearing surface of the foot. The knob and the shoulder upon which it seats preferably have complementary spherical bearing surfaces accommodating swiveled movement between these parts when the sleeve is tilted with respect to the foot. However, this is not required in some cases. In one embodiment herein disclosed, the knob cannot tilt on its seat on the sleeve shoulder and pivotal movement between the sleeve and foot is accommodated by the elasticity of the stem. Various other knob forms are contemplated.

The glide foot normally has substantial area and marginal relief and is made of non-marking material to slide smoothly on the floor or floor covering. The present invention takes advantage of the large area of the foot so that load imposed on the glide is sustained in compression and well distributed. The concave annular bearing surface may be formed either directly upon the foot or, in preferred embodiments, upon a decorative socket ring which is interchangeably carried by the foot and which, for reasons hereinafter noted, rests peripherally on the foot when unloaded, the ring being slightly resilient and having its central portion spaced slightly above the foot at its inner periphery for limited axial yielding movement.

When the knob and the leg plug or sleeve both have spherically convex bearing surfaces, as in the preferred construction hereinafter described, these surfaces are not necessarily concentric, although they are nearly so. Preferably they are offset slightly axially of the sleeve, whereby there is relatively little resistance to swivelling action of small angle, the resistance progressively increasing as the angle increases.

Since the shouldered portion of the sleeve or leg plug is confined between the knob and the concave bearing surface of the foot, it is necessary to make segments of the leg plug or sleeve separable to facilitate assembly. To this end, the leg plug may be axially split, at least at the end thereof which carries the shoulder, so that the resulting shouldered segments of the sleeve can be separated to receive the knob. With the knob in place and the shouldered segments of the leg plug confined about the knob either by the leg itself or by a ferrule, the leg-connected and foot components of the device are securely anchored in connection with each other to maintain the parts in assembly during handling and use, while accommodating universal tilting movement of the foot with respect to the furniture leg to which the leg-connected components of the glide are attached.

In the drawings:

FIG. 1 is a view in side elevation of a swivel glide embodying the invention as it appears when the leg-connected parts are pivoted out of alignment with the foot.

FIG. 2 is a view taken in axial section through the device of FIG. 1 with the several parts in axial alignment,

2

the foot and its stem and knob being shown in side elevation.

FIG. 3 is an exploded perspective view of the component parts of the swivel glide shown in FIGS. 1 and 2.

5 FIG. 4 is a view similar to FIG. 2 showing in section a somewhat modified embodiment of the invention.

FIG. 5 shows a glide embodying the invention assembled to a tubular furniture leg, the leg and parts of the glide being illustrated in section.

10 FIG. 6 shows a glide embodying the invention assembled to a solid furniture leg, the leg and parts of the glide being illustrated in section.

FIG. 7 is a sectional view showing a further modified embodiment of the invention.

15 The preferred construction will first be described, it being understood that various changes in form may be made within the contemplation of the invention.

The foot assembly A comprises a foot 10 having a glide surface 12 marginally relieved at 14 and provided 20 with a central boss 16 which assists in centering on the upper surface 18 of the foot a socket ring 20 which is separately prefabricated principally in order that it may be interchangeable with respect to the foot for decorative reasons. Since this ring is preferably made of plastic, 25 which is available in any desired color, the interchangeable feature permits the glide to be conformed with any desired color scheme, simply by equipping the foot with a socket ring of appropriate color. But for this, the concave bearing surface 22 might be provided directly upon the foot.

30 The socket ring 20 has a central opening telescopically engaged with the boss 16 of the foot. Its lower surface 24 is slightly dished or downwardly concave so that the socket ring is engaged with the foot only at its outer periphery until subjected to load. The synthetic resin of 35 which the socket ring is preferably molded has sufficient resilience so that the inner periphery of the ring yields axially under load, thus providing a measure of springiness and also tending to vary slightly the radius of the spherically concave bearing surface 22, when load is imposed thereon. The resilient yielding of socket ring 20 is 40 not a requisite of the invention. In fact, in some embodiments the ring in question is made of metal rather than synthetic resin.

45 The foot components further include a stem or post 26 which rises centrally from the boss 16 and which carries a knob 28. In the embodiment shown in FIGS. 1 to 3, this knob has the form of a truncated sphere with a central cavity at 30, the principal purpose of the cavity being to 50 reduce the amount of material required in the fabrication thereof. Externally, the knob or head 28 preferably has a generally spherical bearing surface 32, although surfaces of other contours are usable. While the surface 32 may be concentric with the bearing surface 22 of the socket ring 55 20, it is preferred that the center 34 of the spherical surface 32 be offset slightly in a direction axially of post 26 of the center 36 of the spherical bearing surface 22 (FIG. 2).

The leg-connected components B of the glide are subject to considerable variation according to whether the glide is to be used with a hollow leg or a solid leg. The construction shown in FIG. 1 to FIG. 3 is used with a hollow leg. It includes a leg plug or sleeve 40 receivable within the hollow tubular leg 38 and provided with a convex bearing surface 42 engaged with and generally complementary to the bearing surface 22 of the socket ring.

70 The sleeve 40 is internally shouldered to provide a seat 44 extending beneath the knob 28 and with which the knob is engaged to maintain the leg-connected components B and the foot components A in assembly. In the preferred construction, the bearing surface of seat 44 is spherical to conform to that of the preferred knob.

Between the annular convex external bearing surface 42 of the leg plug or sleeve 40 and the annular internal concave bearing surface 44 thereof, extends an opening 46 through which the post 26 extends. The difference in radius between the interior surface of the leg plug or sleeve 40 and the post 26 is sufficient to allow a very substantial angular pivotal movement between the leg-connected parts and the foot.

In the assembled device, the portion 48 of the leg plug or sleeve which bounds the opening 46 is confined between the knob 28 and socket ring 20. In order to permit assembly, the leg plug or sleeve 40, or at least the shouldered lower end thereof, is divided into segments. This may be done by providing at least one diametrical slit 50 best shown in FIG. 3 so that the shouldered lower extremity of the sleeve can be spread to receive the knob in the manner shown in FIG. 2. As hereinafter explained, means is provided for holding the segments together about the knob and stem. Assuming that the slit does not completely divide the leg plug or sleeve, the slit may terminate in a transverse bore or bores 52 which tend to protect the upper end of the sleeve from being torn when the lower end portions are separated to be engaged over the knob.

When the leg plug or sleeve 40 is engaged in the lower end of a tubular leg as shown at 38 in FIG. 2, its shouldered bearing portions will be confined against radial separation and thereby securely anchored about the knob. It is, therefore, unnecessary to employ for that function a ferrule such as that shown at 54. However, partly for decorative finish and partly to prevent the plastic leg plug or sleeve from being cut by the potentially jagged lower end of the furniture leg 38, it is preferred to provide a ferrule 54 counterbored to receive the leg and having a shoulder at 56 upon which the lower end of the leg rests when the ferrule is seated upon the shoulder 58 with which the leg plug or sleeve is preferably provided.

As will be apparent upon comparison of FIG. 1 with FIG. 2, the arrangement permits of a very substantial range of universal angular tilting movement between the furniture leg and the foot, the range of such movement being sufficient to accommodate any deviation from level which can reasonably be anticipated.

The construction is also very versatile from the standpoint of materials usable. While all of the parts are preferably molded of some flexible and elastic synthetic resin of appropriate low frictional characteristics, nylon being an example, the shoe or foot 10 with its post 26 and knob 28 may conveniently be made of smooth and non-corrosive metal is desired, whether or not the socket ring and leg plug are made of plastic. Similarly, the leg ferrule may be made of metal, if desired. In fact, the parts may be made of any desired materials.

In the construction shown in FIGS. 5 and 6, the only differences from that above described lie in the arrangement whereby the leg plug 400 is shown closed at its upper end 60. The long tapered side openings 62 take the place of the slits 50 and bores 52 of FIGS. 2 and 3. The showing of FIG. 5 also exemplifies the statement above made to the effect that the ferrule 54 may be omitted, the tubular leg 38 being seated directly on the shoulder 58. FIG. 6 shows that by using a ferrule at 540 which extends well above the leg plug 400, the ferrule may be made to receive the lower extremity of a solid leg such as that shown at 380. It will, of course, be understood that the device shown in FIGS. 1 to 3 is similarly adapted to receive a solid leg when an appropriate ferrule is used.

By way of an extreme exemplification of the fact that the engaged surfaces of the knob and its seat on the shouldered sleeve need not be spherical and need not necessarily provide a bearing, FIG. 7 shows a further modified embodiment in which the knob 281 is externally cylindrical rather than having the form of a truncated sphere. It is fitted into a complementary generally cylindrical socket in the leg plug or sleeve 401 and seats on a shoulder 441.

which is flat instead of being spherical, it being understood that the shoulder and knob may be of any desired form. In the construction of FIG. 7, the required swiveled movement between the leg plug or sleeve and the socket ring 29 is accommodated by the flexibility and axial attenuation of the elastic stem 261 so that swivelling movement between the foot components and the leg-connected components can occur in the desired manner and through great range of universal angular movement. In this case, the upper end of the frusto-conically tapered interior opening 461 in the sleeve may have the same radius as the elastically flexible and stretchable stem 261, since no relative lateral movement is required.

It will be understood that the various features disclosed are interchangeable between the various embodiments.

Swivel glides embodying the invention are readily manufactured and shipped in assembled form or with the various components separated for assembly by the furniture manufacturer or user. Either at the time of initial purchase or any future time the socket rings, leg plugs or ferrules may be disassembled and interchanged to vary the color scheme of the unit. Assuming that the components or some of them are made from an appropriate synthetic resin such as nylon, the arrangement provides a self-lubricating assembly which is free of corrosion and does not mark a floor upon which it is used. Moreover, the concave form and large area and large radius of the annular bearing surfaces upon which the leg-connected parts are supported from the shoe assures that the loading will be light and the material used will have long life without abrasion. The preferred construction as above described tends to be self-centering and the connection between the leg-connected components and the shoe-connected components is advantageously made through the center of the annular bearing surfaces, thus accommodating substantial increase in radius and area of such surfaces, as compared with other assemblies.

I claim:

1. A furniture leg glide for use with a tubular member and comprising a foot member provided centrally with an upright stem having a terminal knob spaced above the member and having materially greater cross section than said stem, means providing a concave annular bearing surface on the foot member and encircling the stem, an integral sleeve of flexible material having a lower end portion split to receive the knob, said lower end portion being provided internally with an annular shoulder underlying the knob and surrounding the stem and said sleeve also having an exposed lower surface which is downwardly convex and is seated on the said concave bearing surface for universally yieldable support from the foot member, the split lower end portions of the sleeve being held closed about the knob by said tubular member.

2. A glide according to claim 1 in which the knob and interior of the sleeve have complementary cylindrical surfaces and the stem is flexible.

3. A glide according to claim 2 in which the shoulder is substantially normal to the stem.

4. A glide according to claim 1 in which the interior of the sleeve is substantially cylindrical at the level of the top of said head, the annular shoulder and lower portion of the head having mating spherical surfaces in bearing contact.

5. A slide in accordance with claim 1 in which said concave annular bearing surface first mentioned is generally spherical about a center spaced axially of the sleeve from the center of the annular spherical surface of the shoulder of the sleeve.

6. A glide in accordance with claim 1 in which the engaged surfaces of the knob and shoulder deviate from parallelism with the said bearing surfaces of the foot and sleeve, and the stem is sufficiently elastically extensible and flexible to accommodate movement between said bearing surfaces.

7. A glide according to claim 1 in which said sleeve has an external shoulder upon which said tubular member is seated.

8. A glide according to claim 1 in which the means providing the concave annular bearing surface first mentioned comprises a socket ring separately prefabricated.

9. A glide according to claim 1 in which the sleeve has an external shoulder surrounding the inner shoulder upon which the knob is seated, said tubular member having a lower terminal portion embracing said sleeve and seated upon the external shoulder thereof, and having its upper end extended above said sleeve and adapted to receive a furniture leg for which the sleeve provides support from said foot member.

10. A glide according to claim 1 in which the means providing the concave annular bearing surface first mentioned comprises a socket ring separately prefabricated,

said foot member having a central boss telescopically engaged by the inner periphery of said ring.

11. A glide according to claim 10 in which said foot and ring are respectively provided with opposed surfaces engaged substantially only adjacent the outer periphery of said ring when the ring is unloaded, the inner periphery of the ring being spaced axially above the foot member adjacent said boss and the sleeve being wholly supported thereon, the ring being resiliently yieldable under load.
